UNITED STATES PATENT OFFICE.

ALGIE P. DAVIS, OF WHITE ROCK, COLORADO, ASSIGNOR OF ONE-THIRD TO WINTHROP
S. DAVIS, OF WHITE ROCK, COLORADO.

WIRE-HOLDER.

1,313,795.

Specification of Letters Patent. Patented Aug. 19, 1919.

Application filed December 14, 1917. Serial No. 207,175.

To all whom it may concern:

Be it known that I, ALGIE P. DAVIS, a citizen of the United States, residing at White Rock, in the county of Pueblo and 5 State of Colorado, have invented new and useful Improvements in Wire-Holders, of which the following is a specification.

This invention has reference to means for holding the line wires of fences on a post, 10 and means for facilitating the insertion of said wire holding means in the post.

The primary object of the invention is to produce a wire holding member including a slotted or bifurcated end and a barbed shank, 15 the members providing the head having registering openings, the line wire designed to be received in the slot of the head, and a securing element passing through the alining openings in the head for retaining the 20 wire on the head.

It is a further object of the invention to produce a wire holding member constructed from a single strand of wire and designed, from a single operation of a suitable machine, to be pointed, barbed, and headed, and 25 whereby a great number of the holders may be easily and quickly produced.

It is a further object of the invention to produce a wire holding member having a bifurcated outer end or head and a barbed shank and to provide a cap designed to engage with the head to receive the arms provided by the bifurcation thereof, so that an 35 impact of force, such as a blow of a hammer may be directly received by the cap to prevent injury to the head of the wire holding member when the latter is to be inserted in a post.

It is a still further object to produce a device 40 of this construction which shall be of a simple nature, cheap in construction and thoroughly efficient for the purpose devised.

In the drawings,

Figure 1 is a perspective view of a barbed 45 wire fence, the line wires being secured on the posts in accordance with this invention.

Fig. 2 is a view illustrating the arrangement 50 of the cap on the head of one of the wire holding members to facilitate the insertion of the said member in the post.

Fig. 3 is a perspective view of one of the wire holding members.

Fig. 4 is an approximately central longitudinal sectional view through the cap and

through the head of the wire holding members.

Fig. 5 is a perspective view of the cap.

The fence posts are indicated by the numeral 7, and the line wires comprising the fence by the numerals 8. The wires are received in the bifurcated ends or heads of holding members constructed in accordance with this invention.

The details of the construction of the holder members will hereinafter be fully 65 set forth, but it is to be here stated that the holding members are constructed of wire of a suitable gage, a length of such wire being fed through a suitable machine, designed to point, barb and head portions thereof to produce a great number of the holders, each at 70 a single operation of the machine, at a minimum amount of time. It is also to be noted that the barbs on the shanks of the holder members are arranged on the sides thereof 75 in a line with the slots in the heads, so that the heads, when receiving the line wires therein, the weight of the said line wires, or any other weight added to the line wires will not weaken the holder as would be the case 80 were the barbs arranged upon the opposite sides of the shank, or in other words, in a line with the outer faces of the head of the holder.

Each of the holding members includes a 85 shank, the diametrically opposite sides of which, inward of the point thereof, barbed as at 10, and the outer end of the shank is widened providing what I will term a head 90 11. This head, from its outer end, is centrally slotted by the machine, so that the said head is divided into two spaced parallel arms or members 12 respectively, the inner faces of the arms being straight, but the outer faces being round conforming to 95 the cross sectional contour of the wire from which the said arms are formed. The barbs 10 are provided by cutting the shank on the sides thereof in a line with the opening in the head both transversely and angularly, 100 thus presenting straight shoulders 10' and angle surfaces 10'' between the shoulders. It will be noted that the angular surfaces 10'' are directed toward the point of the shank, and that the barbs being formed by cutting or pressing the sides of the shank provide 105 no protrusions on the said sides, so that the shank may be readily inserted in the post.

The members 12 adjacent the outer ends thereof are provided with alining openings 13, and through these openings is designed to be passed a preferably bendable member 14 that may be twisted around the head to effectively secure the wire 8 in the pocket therefor, between the arms 12 of the head. It is, of course, obvious that other retaining means may be employed, as for instance, 10 the bolt may be passed through the openings 13, one of the said openings may be provided with threads to engage with the threads of the bolt or the said bolt may pass entirely through the openings, and have its 15 threaded end engaged by a nut, while still again, the retaining element may be in the nature of a cotter pin.

To facilitate the insertion of the wire holding members in the post 7, I provide a cap 20 indicated by the numeral 15. This cap, from what may be termed the inner end thereof, is formed with two spaced longitudinally extending slots or depressions 16 which are designed to receive the arms 12 25 of the head, and the dividing member between the depressions or what may be termed the partition 17 is designed to be received in the slot between the arms 12 of the head. The outer walls of the depression 30 are rounded to receive the outer rounded surfaces of what I have termed arms of the head. Thus it will be noted that the arms, by the contacting engagement therewith of the partitions 17 are held from 35 inward movement with respect to each other and by virtue of the contact of the side walls of the cap, the said arms are held against outward movement. The cap is constructed of tough material, such as harveyized steel, 40 so that the same will effectively withstand the impact of force delivered thereon by

the blows from a hammer or other similar driving element.

The cap is provided with a handle portion 18 so that the said cap may be effectively held when the head of the holder member is arranged therein, and properly positioned with respect to the position for the insertion of the said holder member in the post. 45

From the foregoing description, when taken in connection with the accompanying drawings, the simplicity and advantages of the construction will, it is thought, be apparent without further detailed description. 50

Having thus described the invention, what I claim is:

1. In combination with a fence post designed to receive line wires of a fence, of a wire holder including a shank and a bifurcated head, said shank being barbed on the 60 sides thereof in a line with the bifurcation of the head, said head having openings therethrough, and a wire retaining element passing through said openings and secured to said head. 65

2. A wire holding member for fence posts, comprising a shank having an inner pointed end, said shank being round in cross section and being formed inward of its pointed end with barbs, presenting straight shoulders 70 and angular walls between said shoulders, the shank being centrally bifurcated to provide a head, the members constituting the head being spread apart at the inner end and from thence continued in parallelism, 75 said arms having registering openings designed to receive an element for retaining a wire in the bifurcated portion of the head, and said element adapted to be secured to the head. 80

In testimony whereof I affix my signature.
ALGIE P. DAVIS.

Copies of this patent may be obtained for five cents each, by addressing the "Commissioner of Patents, Washington, D. C."
